UNITED STATES PATENT OFFICE.

CHARLES W. HOTTMANN, OF PHILADELPHIA, PENNSYLVANIA, ASSIGNOR OF ONE-HALF TO AUGUST H. E. JUERGENS, OF PHILADELPHIA, PENNSYLVANIA.

SPEED-CHANGING MECHANISM.

1,113,635.

Specification of Letters Patent.

Patented Oct. 13, 1914.

Application filed August 6, 1912. Serial No. 713,517.

To all whom it may concern:

Be it known that I, CHARLES W. HOTTMANN, a subject of the Emperor of Germany, having resided in the United States one year last past and having declared my intention of becoming a citizen thereof, residing in the city and county of Philadelphia, State of Pennsylvania, have invented a new and useful Speed-Changing Mechanism, of which the following is a specification.

My present invention in its broad and generic scope consists of a novel speed changing mechanism wherein the power is transmitted from the driving to the driven member through the medium of a fluid of any desired nature.

It further consists of a novel speed changing mechanism having a fluid connection between the driving and driven member and novel means for varying the compression of the fluid between such members to vary their relative speed of rotation.

It further consists of a novel construction of speed changing mechanism of the character described in which I have eliminated the necessity of employing valves or complicated mechanisms to control the introduction of fluid into the fluid chamber.

It further consists of other novel features of construction, all as will be hereinafter fully set forth.

For the purpose of illustrating my invention, I have shown in the accompanying drawings those forms which are at present preferred by me, since the same have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a sectional elevation on line $\alpha-\alpha$ of Fig. 2 of a speed changing mechanism embodying my invention. Fig. 2 represents a sectional elevation of my device. Fig. 3 represents a sectional elevation of a portion of my device showing certain parts in a different relation from that seen in Fig. 1. Fig. 4 represents a sectional elevation showing the parts in the position they assume when the plunger is in the position seen in Fig. 3. Fig. 5 represents a sectional view of a portion of my device show-

ing certain parts in a different position from that seen in Figs. 2 and 3. Fig. 6 represents an end elevation of another embodiment of my invention certain parts having been removed for the sake of clearness of illustration.

Similar numerals of reference indicate corresponding parts in the figures.

Referring to the drawings, 1 designates the driving member and 2 designates the driven member which latter is shown as forming a pulley although it will be apparent that the outer periphery 3 may be in the form of a gear, sprocket wheel, or equivalent device. The driven member 2 is loosely mounted on the driving member 1 and is provided with a removable end 4 secured thereto in any desired manner and, in the present instance, by means of fastening devices 5.

6 designates a stuffing box of any desired type carried by the driven member 2 to prevent any leakage of fluid between the driving and driven member at such point. In the present instance I have shown my novel device as located at the end of the driving shaft, the hub of the end member 4 and of the driving member 1 being mounted in a conventional type of support 7. The end of the driving member 1 is hollow, as indicated at 8, thereby adapting the same to receive a longitudinally adjustable adjusting member 9 which, in the present instance, consists of a rod or plunger provided with a desired number of wedges such as for example 10 and 11 thereby forming shoulders 12 and 13. The end of the adjusting member 9 extends through a stuffing box 14 provided with a collar 15 to which is operatively connected an actuating lever 16 which is pivoted in the support 7 and is provided with a manually adjustable locking pin 17 which engages with the rack 18 in order to lock the lever 16 in the adjusted position given thereto it being understood that any desired means may be employed for causing the longitudinal adjustment of the member 9, the device shown being simply a conventional manner of accomplishing this result.

19 designates an annulus or collar fixed on the driving member 1 and having at its outer periphery a flange 20 whereby a desired number of annular chambers such as 21 and 22 are formed between the outer periphery of the annulus 19 and the inner face 110

of the driven member 2, as will be clearly apparent from Fig. 1. The outer wall of the annulus 19 is apertured as indicated at 23 in order that a plunger 24 may extend therethrough and into the annular chamber formed between such annulus and the driven member 2. The stem of the member 24 extends through the hub 25 of the annulus 19 which is apertured for this purpose and also through a shaft 1 as will be understood by reference to the figures of the drawings.

26 designates a pin extending through the stem of the plunger 24 and owing to the provision of a spring 27 said pin 26 is always maintained in engagement with one of the wedges on the adjusting member 9. In the present instance, the driving shaft 1 is slotted or apertured, as indicated at 28, in order that the pin 26 may pass therethrough when the device is being assembled, it being understood that the hub 25 is also apertured, as indicated at 29 in order to permit the stem of the plunger 24 to pass therethrough. In the embodiment seen in Figs. 1 to 5 inclusive, I have shown a plurality of plungers, the plunger 30 and its adjuncts corresponding in construction to the plunger 24 already described and being provided with a pin 31 coöperating with the wedge 11 of the adjusting member 9.

32 designates cams or releasing members secured to the driven member 2 by means of fastening devices 33 and having their outer faces corresponding to the inner periphery of the member 2 while the inner faces thereof are substantially straight and bear against the outer periphery of the annulus 19 so as to be in that path of the plungers, it being understood that one of these releasing members 32 is provided for each annular chamber, which closes such chamber at one point in its circumference, the releasing member 34 which is located in the annular chamber 22 being indicated in dotted lines in Fig. 1. In Fig. 6 I have shown another embodiment of my invention in which three of these plungers are employed and therefore three annular channels and three releasing members such as 35, 36 and 37, the members 36 and 37 being indicated by dotted lines.

I have preferred to illustrate the plungers 24 and 30 as being in alignment.

The operation of my novel speed changing mechanism will now be readily apparent to those skilled in this art. The chamber 38 is filled with any desired fluid but preferably with a fluid having lubricating qualities such as for example oil. Since the web 39 is apertured, as indicated at 40, such fluid may freely pass therethrough it being understood that the annular chambers 21 and 22 are also filled with this fluid and if any leakage occurs in such chambers the centrifugal force will cause them to be refilled. Assum-

ing that the plungers are in the position seen in Fig. 5 and that the driving shaft 1 is revolving, the driven member 2 will remain stationary. If, however, the adjusting member 9 is moved outwardly, for example into the positions seen in Figs. 3 and 4, there will be a compression of the fluid in the annular chambers 21 and 22 and the driven member 2 will be revolved, it being understood that as the plungers reach the releasing member 32 they will be moved inwardly against the tension of the springs provided therefor and as soon as they pass such members the springs will cause such plungers to automatically move outwardly, it being understood that a certain amount of the fluid may pass rearwardly between the end of such plungers and the outer wall of the annular chambers. Assuming now that the adjusting member 9 has been moved into the position seen in Fig. 2, the pins 26 and 31 will move upwardly on the wedges 10 and 11 respectively so that the driven member will be revolved at maximum speed. It will thus be apparent that by varying the position of the plungers any desired ratio of speed between the driving and driven members may be obtained.

Since I employ a plurality of annular chambers arranged in different vertical planes and a plurality of plungers and releasing members, the latter being located at different points, there is no possibility of lost motion to any material degree and one or more of the plungers are always in operation.

Special attention is directed to the fact that in my present invention, I have entirely dispensed with the necessity of employing valves and controlling means therefor to control the admission or discharge or both admission and discharge of fluid with respect to the annular chambers and I depend entirely upon centrifugal action to replace any loss of fluid from the annular chambers due to leakage between the moving parts. Attention is also directed to the fact that all of the plungers are actuated by a common unitary member to simultaneously control the same so that all of these members will extend into their respective annular chambers a predetermined distance.

I have found in practice that by the use of my novel device the driven mechanism may be gradually started or stopped and that any desired ratio of movement between the same may be readily and quickly obtained.

It will now be apparent that I have devised a novel and useful construction of a speed changing mechanism which embodies the features of advantage enumerated as desirable in the statement of the invention and the above description, and while I have, in the present instance, shown and described

a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a speed changing mechanism, a driving member, a driven member forming therewith a plurality of annular fluid chambers, a plunger for each chamber, carried by said driving member and adapted to be automatically moved into its respective chamber, an actuator having wedge shaped portions coacting with each of said plungers to control its movement with respect to its chamber, and a member in each chamber completely closing the same and adapted to move a plunger out of its chamber.

2. In a speed changing mechanism, a driving member, a driven member forming therewith an annular fluid chamber, a plunger adapted to move into said chamber, yielding means for causing such movement of the plunger, means to completely close said chamber at one point and an actuator within the driving member and having sliding engagement with said plunger to limit its movement into said chamber.

3. In a speed changing mechanism, a driving member, a driven member forming therewith an annular fluid chamber, a plunger adapted to move into said chamber, yielding means for causing such movement of the plunger, means to completely close said chamber at one point, an actuator within the driving member and having sliding engagement with said plunger to limit its movement into said chamber, and means for locking said actuator in the adjusted position given thereto.

4. In a speed changing mechanism, a driving shaft, an annulus fixedly carried by said driving shaft thereon, a driven member forming with the outer periphery of said annulus a plurality of annular fluid chambers, spring pressed plungers adapted to pass into said chambers and having their ends extending into said driving shaft, an adjusting device within said driving shaft having means coacting with said plungers to adjust their position within said chambers, and a device within each chamber to cause a plunger to be moved out of said chamber during each revolution of said driving member.

5. In a speed changing mechanism, a driving shaft, an annulus thereon having a flange at its outer periphery, a driven member loosely mounted on said driving shaft and forming with said annulus a plurality of annular fluid chambers, a plurality of plungers, one for each chamber and adapted

to move thereinto, resilient means for causing such movement, a rod within said driving shaft and limiting the movement of said plungers, and a releasing device for each chamber to completely close the same at one point and coacting with a plunger to move the latter out of its chamber.

6. In a speed changing mechanism, a driving member including an annulus having a flange at its outer periphery, a driven member comprising a casing loosely mounted on said driving shaft, inclosing said annulus to form a plurality of fluid chambers, and adapted to drive other mechanism, plungers carried by said annulus and adapted to move into said chambers, springs for causing such movement, an adjusting device within said driving member for limiting the movement of said plungers into said chambers, and a wedge for each chamber and carried by said driven member and closing each chamber at one point in its circumference.

7. In a speed changing mechanism, a driving and a driven element forming therebetween an annular chamber of substantially uniform diameter, a member rotatable with one of said elements and completely closing said chamber at one point, a plunger carried by the other element, adapted to automatically move into said chamber, and to be moved out of said chamber by said chamber closing member, and means within said driving element to adjust the stroke of said plunger.

8. In a speed changing mechanism, two rotatable elements forming therebetween an annular fluid chamber, a plunger mounted for radial movement into said chamber, means to automatically cause such movement, means to adjust the amount of such movement, a wedge rotatable with one of said elements and completely closing said chamber and coacting with said plunger to move it out of its chamber, a pin carried by said plunger, and means in sliding engagement with said pin to effect the radial adjustment of said plunger.

9. In a speed changing mechanism, two rotatable elements forming therebetween an annular fluid chamber, one of said elements including a hollow shaft, a plunger mounted for radial movement into said chamber, means to automatically cause such movement, means within said hollow shaft to adjust the amount of such movement, means rotatable with one of said elements and completely closing said chamber and coacting with said plunger to move it out of its chamber, and a source of fluid supply inwardly of said annular chamber.

10. In a speed changing mechanism, two rotatable elements forming therebetween a plurality of independent spaced annular chambers arranged in different vertical planes, plungers one for each chamber and

- 1 mounted for movement thereinto, yielding means to simultaneously move said plungers into their respective chambers, devices to close each chamber and to move a plunger 5 out of its chamber as said plunger contacts with said devices, and means to vary the position of the plungers with respect to their chambers whereby the relative speed of rotation of said elements may be varied, said 10 last-named means comprising a plunger having a plurality of wedge-shaped faces thereon forming shoulders, and pins carried by said plungers and in sliding engagement with said wedge-shaped faces.
- 15 11. In a speed changing mechanism, two rotatable elements forming therebetween a plurality of independent spaced annular chambers arranged in different vertical planes, plungers one for each chamber and 20 mounted for movement thereinto, yielding
- means to simultaneously move said plungers into their respective chambers, devices to close each chamber and to move a plunger 25 out of its chamber as said plunger contacts with said devices, said devices in said chambers being out of alinement with each other, means to vary the position of the plungers with respect to their chambers whereby the relative speed of rotation of said elements may be varied, said last-named means comprising a plunger having a plurality of wedge-shaped faces thereon forming shoulders, and pins carried by said plungers and in sliding engagement with said wedge-shaped faces. 30
